(57) **CLAIM**

The ornamental design for a fluidic cassette, as shown and described.

DESCRIPTION

FIG. 1 is a front, top, and first side perspective view of the fluidic cassette;

FIG. 2 is a top view thereof;

FIG. 3 is a bottom view thereof;

FIG. 4 is a front view thereof;

FIG. 5 is a back view thereof;

FIG. 6 is a first side view thereof;

FIG. 7 is a second side view thereof;

FIG. 8 is an exploded perspective view thereof;

FIG. 9 is a front, top, and first side perspective view of a second embodiment of the fluidic cassette;

FIG. 10 is a top view thereof of the second embodiment;

FIG. 11 is a front view thereof of the second embodiment;

FIG. 12 is a back view thereof of the second embodiment;

FIG. 13 is a first side view thereof of the second embodiment;

FIG. 14 is a second side view thereof of the second embodiment; and,

FIG. 15 is a exploded perspective view thereof of the second embodiment.

Those portions of the Figures shown in broken lines depict features that form no part of the claimed design.

1 Claim, 11 Drawing Sheets
